UNITED STATES PATENT OFFICE.

FRANK J. NIES, OF EAST ORANGE, NEW JERSEY.

SHED-VENTILATOR.

No. 901,120.

Specification of Letters Patent.

Patented Oct. 13, 1908.

Application filed May 6, 1908. Serial No. 431,139.

To all whom it may concern:

Be it known that I, FRANK J. NIES, a citizen of the United States of America, and residing at East Orange, in the county of Essex and State of New Jersey, have invented 5 certain new and useful Improvements in Shed-Ventilators, of which the following is a specification, such as will enable those skilled in the art to which it appertains to make and use the same.

This invention relates to sheds and particularly to train sheds as employed at railway stations and terminals, and the object thereof is to provide means for gases, vapors and vitiated air to pass outward into the open air and not permit rain, sleet or snow to pass therethrough beneath the shed; a further object being to provide ventilating means for sheds at present constructed 20 without a material change therein; a further object being to provide means whereby winds are prevented from entering the said ventilating devices and thereby force said gases, etc. downwardly, but which serve to deflect the said winds and produce an upward current of air through the ventilating devices and thereby carry away the gases, etc. and a still further object being to provide such shed ventilating devices which are 25 simple in construction, comparatively inexpensive in installation and very economical in maintenance.

My invention is fully described in the following specification, of which the accompanying drawings form a part, in which the separate parts are designated by the same reference characters in each of the views, and in which:—

Figure 1 is a section taken transversely 40 through a train shed constructed according to my invention; Fig. 2 is a longitudinal section taken through one of the ventilating devices; and Fig. 3 is an enlarged, fragmentary, perspective view of one of the 45 ventilating devices in position.

In the drawings forming a part of this application, I have shown a train shed a , comprising columns a^2 and an arched roof a^3 provided with a plurality of longitudinally 50 arranged air ducts a^4 over the tracks a^5 and completely covering the platforms a^6 , said roof being supported upon girders a^7 . At each side of each of the air ducts a^4 is a vertical apron b which extends entirely through 55 the length of the shed, preferably, or along

that portion thereof occupied by trains or locomotives, said aprons extending both above and below the roof a^3 , as clearly shown, for a predetermined distance. Supported by a plurality of rods c , secured to the aprons b , is a longitudinally arranged cover c^2 for each of the air ducts a^4 , having the under side outwardly flared from the center thereof in order to direct the gases outwardly to each side thereof, said covers 60 being of slightly greater width than the air ducts, and being preferably composed of reinforced concrete, of cast iron, with or without a suitable filling or of any other desired material, calculated to withstand the 65 corroding or action of the said gases. Secured to the rods c are a plurality of outwardly extending bars or brackets d which carry deflectors d^2 for winds and arranged upon each side of each of the covers c^2 and 70 at a great enough distance therefrom to permit the free passage of gases between said covers and deflectors and, in practice, I prefer to curve the said deflectors upwardly and inwardly, and downwardly and outwardly in order to so deflect the said winds 75 as to cause a draft through the air ducts a^4 and prevent the possibility of backdraft.

It will be seen that I provide a plurality 80 of longitudinally arranged air-ducts directly over the locomotives and the trains and through which rain, sleet or snow cannot pass because of the covers c^2 although the said covers permit the free outward passage 85 of gases through the air ducts, said covers 90 being continuous for the entire length of the air ducts, and in connection with which I also provide means for preventing rain and the like from being driven into the shed provided with my invention and for assisting 95 the outward passage of gases and the like, these wind deflecting means being also continued throughout the length of the air ducts and covers a^4 .

While but one form of air duct covers is 100 shown, and but one form of the wind deflectors, it will be apparent that many modifications of the same may be made in order to accomplish the desired results and, reserving the right to all such changes in and 105 modifications of the form shown and described,

What I claim as new and desire to secure by Letters Patent, is:

1. In a shed, the combination of girders, 110

a roof thereon, aprons extending through said roof and forming an air duct, and a cover arranged over said air duct.

2. In a shed, the combination of girders, a roof thereon, aprons extending longitudinally through said roof and forming an air duct and a longitudinally arranged cover above said air duct.

3. In a shed, the combination of girders, a roof thereon, aprons extending through said roof and forming an air duct, a cover over said air duct and members connected with said cover outwardly flared to direct gases from said shed through said air duct.

4. In a shed, the combination of girders, a roof thereon and provided with a longitudinally arranged opening therethrough, a cover arranged at a predetermined distance above said opening forming side openings for the upward and outward passage of gases, and wind deflectors arranged at a distance from said side openings.

5. In a shed, the combination of girders, a roof thereon, provided with a longitudinally arranged opening therethrough, vertical aprons at each side of said opening and a cover for said opening carried by said aprons at a distance thereover.

6. In a shed, the combination of girders, a roof thereon and provided with a longitudinally arranged opening therethrough, a vertical apron at each side of said opening and forming an air duct, a cover for said duct at a distance above said aprons and forming side openings, and wind deflectors arranged before said side openings.

7. In a shed, the combination of girders, a roof thereon, vertical aprons through said roof forming an air duct, a cover above said air duct and forming side openings, and wind deflectors before said side openings, said deflectors being downwardly and outwardly flared.

8. In a shed, the combination of girders, a roof thereon and provided with a longitudinally arranged opening therethrough, a

cover at a distance above said opening and forming side openings, and upwardly and inwardly flared deflectors in front of said side openings.

9. In a shed, the combination of girders, a roof thereon and provided with a longitudinally arranged opening therethrough, a cover at a distance above said opening and forming side openings and deflectors, upwardly and inwardly flared and downwardly and outwardly flared, before said side openings.

10. In a shed, the combination of girders, a roof thereon and provided with a longitudinally arranged opening therethrough, a cover, upwardly and outwardly flared, above said opening and forming side openings and means for preventing entrance of winds into said side openings.

11. In a shed, the combination of girders, a roof thereon and provided with a longitudinally arranged opening therethrough, a cover, upwardly and outwardly flared in two directions above said opening and forming side openings and means for preventing the passage of winds into said side openings.

12. In a shed, the combination of girders, a roof thereon and provided with a longitudinally arranged opening therethrough, a cover, upwardly and outwardly flared, above said opening and deflectors, inwardly and outwardly curved, at each side of said opening.

13. In a shed provided with a longitudinally arranged opening through the roof thereof; a longitudinally arranged cover upwardly and outwardly flared above said opening.

In testimony that I claim the foregoing as my invention I have signed my name in presence of the subscribing witnesses this fifth day of May, 1908.

FRANK J. NIES.
